T. S. Hudson.
Design for Ink Stand

4705

PATENTED MAR 14 1871

United States Patent Office.

THOMAS S. HUDSON, OF EAST CAMBRIDGE, MASSACHUSETTS.

Design No. 4,705, dated March 14, 1871.

DESIGN FOR AN INKSTAND.

The Schedule referred to in these Letters Patent and making part of the same.

To all whom it may concern:

Be it known that I, THOMAS S. HUDSON, of East Cambridge, in the county of Middlesex and State of Massachusetts, have invented or produced an Improved Design for Inkstands; and I do hereby declare that the following, taken in connection with the drawing which accompanies and forms part of this specification, is a description of my invention sufficient to enable those skilled in the art to produce it.

My invention relates—

To an ornamental construction of inkstands, and consists in a glass stand, having the form of the hull of a side-wheel steamer, the central part of the hull having a representation of the wheel and wheel-house, the lower portion of which serves as the base or support of the stand; and there being on the forward deck and on the aft or quarter deck two "inks," or ink-holders, covered by caps, while in the center, or amidships, there may be made a chamber for a sponge.

The drawing shows in side elevation, in sectional elevation, in end view, and in plan, a glass inkstand embodying my improved design.

a represents the hull, which may be molded with depressions *b*, to represent sheathing.

c is the stem, and

d the stern of the hull.

e denotes the wheel-house, under which is the base *f*, that supports the stand in position.

g is the forward ink, and *h* the aft ink, each being simply a chamber formed in molding the stand. Each is shown as covered by a cap, *i*.

In the center there may be a square chamber, *k*, made for reception of a sponge.

The whole design makes a very ornamental, well-proportioned, and useful ink-receptacle, for use upon desks or tables, the two inks being almost indispensable wherever there is much writing, one for fluid and one for copying ink, one for black ink and one for blue or red ink.

I claim—

The design for an inkstand, consisting of a representation of the hull of a vessel, with two "inks" forward and aft, as shown, and with or without a sponge-cup between the inks.

THOS. S. HUDSON.
